FIG. 2

FIG. 3

INVENTOR
Frank E. Neill,
BY

John B. Brady
ATTORNEY

UNITED STATES PATENT OFFICE

149,435

DESIGN FOR A RADIO BROADCAST RECEIVER

Frank E. Neill, Detroit, Mich., assignor of one-half to Richard H. Meigs, Dearborn, Mich.

Application January 24, 1947, Serial No. 136,362

Term of patent 14 years

(Cl. D56—4)

To all whom it may concern:

Be it known that I, Frank E. Neill, a citizen of the United States, residing at Detroit, in the county of Wayne and State of Michigan, have invented a new, original, and ornamental Design for a Radio Broadcast Receiver, of which the following is a specification, reference being had to the accompanying drawing, forming part thereof.

Fig. 1 is a side elevational view of the radio broadcast receiver.

Fig. 2 is an end view of the radio broadcast receiver, looking at the sound reproducer end thereof;

Fig. 3 is a view looking at the opposite end of the radio broadcast receiver; and

Fig. 4 is a perspective view of the radio broadcast receiver showing my new design.

The side opposite to that shown in Fig. 1 is a plain unornamented surface.

I claim:

The ornamental design for a radio broadcast receiver, as shown and described.

FRANK E. NEILL.
